UNDERFEED STOKER

Gilbert M. Seaman, Catskill, N. Y.

Original application April 21, 1933, Serial No. 667,245. Divided and this application January 22, 1935, Serial No. 2,857

2 Claims. (Cl. 110—45)

This is a division of my co-pending application, Serial Number 667,245, filed April 21, 1933.

My invention relates to mechanical underfeed stokers for coal-burning furnaces and the like; and it has for its object to provide dependable means for preventing discharge of gases of combustion (hopper smoke) from the furnace by way of the fuel-feed conduit and thence through the fuel hopper to the ambient atmosphere.

10 In furnaces equipped with mechanical underfeed stokers of the character here dealt with, the coal or other solid fuel is delivered from a hopper through a fuel-feed conduit, by means of a feed screw, to the bottom of a retort and thence upwardly through the retort wherein combustion occurs.

Due to the fact that air for combustion is delivered to the burning fuel through the perforated wall of the retort and meets with some little resistance in its passage to the flue, and to the further fact that the air is supplied at a pressure above atmospheric, there is a continuous tendency for a back-draft to flow from the interior of the retort through the fuel-feed conduit and thence through the fuel hopper to the atmosphere about the furnace. This back-draft frequently carries with it some of the gaseous products of combustion (unless adequately provided against) and is for that reason both a nuisance and a menace to health. As hereinbefore stated, the present invention is designed to prevent the discharge of such gases other than by way of the flue.

It has previously been proposed, as for example in U. S. Patent Number 1,876,310 to Jacob Madlehner, to introduce into the fuel stream a supply of uncontaminated air under suitable pressure for the purpose of creating a barrier to the gas-laden air which would otherwise be discharged through the fuel-feed conduit and hopper. The principle thus previously expounded is thoroughly sound and is the one underlying the present invention; but the devices and arrangements heretofore proposed for carrying it into effect have in each instance, so far as I have been able to learn, been insufficient, from a practical standpoint, because of susceptibility to becoming clogged and thus rendered inoperative by accumulations of coal dust; and no adequate provision has before been suggested whereby such obstructions could readily be removed.

In the stoker construction of the present invention the auxiliary air duct through which the auxiliary air supply is delivered to the fuel-stream for the purpose of establishing a gas barrier is so

designed and disposed that it does not readily become clogged; and, what is of comparable importance, means are provided whereby this duct can easily and conveniently be cleared by the furnace attendant in event it does, in the course of time, become clogged.

A preferred embodiment of my invention is illustrated in the accompanying drawing wherein:

Fig. 1 is a vertical sectional view of a portion 10 of an underfeed stoker together with the retort or firepot and tuyère chamber—only such parts being shown as are necessary to adequately disclose the invention;

Fig. 2 is a plan view with certain parts broken 15 away in order more clearly to show the inventive features; and

Fig. 3 is a cross-sectional view of the fuel-feed conduit and auxiliary air duct, taken along the line 3—3 of Figs. 1 and 2.

The structure illustrated comprises, as its major components, an iron casting 1, approximately in the form of an inverted truncated cone having a circular lateral opening at 2; a cast iron elbow 3 mounted inside the casting 1; a retort or firepot 4, ordinarily of cast iron, mounted within the casting 1, its upper end resting on the upper flange of casting 1 and its lower end on the upper face of elbow 3; a tubular fuel-feed conduit 5, one end of which projects into the elbow 3; 30 a fuel-feed screw inside the fuel-feed conduit, but not shown in the drawing; and a clean-out rod 6 having a plunger head 7 and handle 8.

The casting 1 together with elbow 3 and retort 4 form, conjointly, a tuyère chamber 9 which surrounds the retort and serves as a conduit for air under pressure above atmospheric which is thus delivered to the interior of the retort through a large number of small openings therein, identified as a group by reference numeral 10. 40 Air under pressure is provided by a suitable blower, not shown, which is connected to the tuyère chamber through the medium of a conduit 11 and manifold 13.

The fuel, which is generally coal of small size, 45 such as buckwheat or rice, is fed slowly by the fuel-feed screw from a fuel hopper, not shown, through the fuel-feed conduit 5 and thence through elbow 3 and upwardly through the retort wherein combustion takes place.

In operation, the retort is filled to overflowing with burning fuel and ashes, fresh fuel constantly moving up from the bottom and air for combustion being introduced under pressure above atmospheric through the numerous openings 10.

It is manifest that the forced draft will carry the greater part of the gaseous products of combustion upwardly to the flue; but it will be apparent, upon reflection, that a part of the draft, after 5 entering the firebed, will tend to pass downwardly through the elbow 3 and out through the fuel-feed conduit and hopper—and that such discharge as might occur in that manner would carry with it some noxious fumes—that being the 10 problem with which the present invention is concerned.

By introducing uncontaminated air under sufficient pressure into the fuel-feed passageway, in 15 advance of the firebed, as, for instance, into the elbow 3, a barrier may be created to the flow of gas-laden air from the firebed through the fuel-feed conduit and hopper—the air thus injected into the fuel-feed passageway creating an upward draft in opposition to the down-draft of gas-laden 20 air. Thus it follows that the only flow of air finding its way out of the fuel hopper by way of the fuel-feed conduit is that of the auxiliary supply which is without contamination and therefore unobjectionable.

25 In the structure illustrated there is provided an auxiliary air duct 12 which, as will be seen, is outside of the fuel-feed conduit and extends in the same direction as the flow of fuel from the fuel-feed conduit and arranged to discharge air 30 into the fuel stream at the point of discharge of fuel from the conduit and in the same direction as the flow of fuel from the conduit. I have found that with the auxiliary air duct thus arranged there is never any discharge of gas 35 through the hopper and there is a minimum of tendency for the duct to become clogged and the auxiliary air supply thus cut off.

It will be observed that the auxiliary air duct 12 10 opens at its intake end into a manifold chamber 13 which is a passageway for the forced draft being delivered to the tuyère chamber and that the air supplied to the auxiliary air duct is accordingly at the same pressure as that in the tuyère 15 chamber or, perhaps, a little higher.

45 The auxiliary air duct 12 arranged as here illustrated and described exhibits a marked tendency to remain continuously free of obstruction; but as an added precaution I have provided means

whereby the furnace attendant can easily and conveniently free the duct from obstruction or prevent it from becoming obstructed by accumulations of coal dust therein. This comprises a reciprocable cleanout rod 6 having a plunger 5 head 7 situated in the duct and an operating handle 8 situated outside the stoker and within easy reach of the attendant. The plunger head 7 is arcuate in form as shown in Fig. 3 and is sufficiently smaller than the duct 12 so that the flow 10 of air is not unduly impeded.

To clear the duct 12 of obstruction or to make certain that it is not obstructed, the furnace attendant simply moves the cleanout rod in and out a few times by means of the handle 8.

What I claim is:

1. In an underfeed stoker, the combination with a hopper, a retort and a fuel-feed conduit connecting said hopper and retort, of means defining a tuyère chamber surrounding said retort, an auxiliary air duct for delivering air under pressure above atmospheric to the fuel stream in advance of said retort, a source of air under pressure above atmospheric connected with said tuyère chamber and auxiliary air duct, and a manually reciprocable cleanout rod extending from the exterior of said stoker into said auxiliary air duct and operable upon manipulation to clear said auxiliary air duct of obstructions.

2. The combination in an underfeed stoker of 30 a hopper, a retort, a fuel-feed conduit connecting said hopper with the bottom of said retort, means defining a tuyère chamber surrounding said retort, a source of air at a pressure in excess of atmospheric connected with said tuyère chamber, an auxiliary air duct connected with said source of air and arranged to discharge into the fuel stream at a point below said retort, and a cleanout rod extending from the exterior of said stoker into said auxiliary air duct, said cleanout rod having 35 a plunger head fitting loosely in said auxiliary air duct so as not to interfere substantially with the flow of air through the duct, said plunger head being operable upon reciprocation of said cleanout rod to free the auxiliary air duct of any 40 obstructive matter which may have accumulated therein.

GILBERT M. SEAMAN.
